(57) **CLAIM**

The ornamental designs for a silicone plate, as shown, and described.

DESCRIPTION

FIG. 1 is a perspective view of a silicone plate;

FIG. 2 is a top view thereof;

FIG. 3 is a bottom view thereof;

FIG. 4 is a right elevation view thereof;

FIG. 5 is a left elevation view thereof;

FIG. 6 is a front view thereof;

FIG. 7 is a rear view thereof; and,

FIG. 8 is a section view thereof taken from line 8-8 in FIG. 2.

The broken lines in the drawings depict portions of the silicone plate that form no part of the claimed design.
